UNITED STATES PATENT OFFICE.

GEORGE HENRY HASEY, OF TAUNTON, MASSACHUSETTS.

PAWL-AND-RATCHET DEVICE.

SPECIFICATION forming part of Letters Patent No. 614,470, dated November 22, 1898.

Application filed August 16, 1898. Serial No. 688,677. (No model.)

To all whom it may concern:

Be it known that I, GEORGE HENRY HASEY, of Taunton, in the county of Bristol and State of Massachusetts, have invented a new and useful Pawl-and-Ratchet Device, of which the following is a specification, reference being had to the accompanying drawings, in which—

Figure 1 is a side elevation, partly in section, of the best form of my device. Figs. 2, 2^a, and 2^b are sections on line 2 2 of Fig. 1 with the ratchet in the same position in all three, but with the pawl-carrier in different positions. Figs. 3 and 4 illustrate a modification, Fig. 3 being a section on line 3 3 of Fig. 4 and Fig. 4 a section on line 4 4 of Fig. 3.

My invention is the combination of a ratchet, a pawl which slides by gravity into engagement with the ratchet, and automatic means which compel the pawl to take a full hold on one of the ratchet-teeth when the ratchet is moved by power applied through the pawl, or vice versa.

In the drawings, A is the pawl-carrier, a the pawl, and B the ratchet. The pawl-carrier A is formed with a socket to receive the ratchet B and is also formed with a chamber at one side to receive the pawl a. The bottom or floor a' of the pawl-chamber is inclined, as plainly shown in Fig. 1, and the lower end of the pawl is also inclined, and the pawl therefore tends constantly to move toward the axis of the ratchet when the spindle b of ratchet B is upright, as shown in Fig. 1.

In order that the pawl will be sure to obtain a full hold on one of the ratchet-teeth when the handle is moved in a direction to cause the pawl to carry the ratchet with it, I provide means to force the engaging end of the pawl toward the axis of the ratchet after the pawl has obtained a partial hold on one of the ratchet-teeth by sliding more or less down the inclined floor a'.

In the form of my device shown in Figs. 1 to 2^b, inclusive, the pawl swings in the pawl-chamber, so that when the handle is moved in one direction the cam action of the ratchet-teeth compels the pawl to swing to clear the ratchet-teeth; but when the handle is moved

in the other direction the pawl will partially engage one of the ratchet-teeth by sliding more or less down floor a' and will then be swung back in its chamber and the engaging end of the pawl will be forced into the full-hold position shown in Fig. 2.

In Figs. 3 and 4 the pawl-carrier A is hinged to handle A' and the rear end of the pawl-chamber is open, the handle A' forming a movable abutment a² for the rear end of the pawl, so that when the handle is moved in one direction the cam action of the ratchet-teeth will move the pawl away from the axis of the ratchet; but on the reverse movement of the handle the pawl will first take a partial hold on one of the ratchet-teeth by sliding more or less down the inclined floor a' toward the axis of the ratchet, and that partial hold of the pawl in one of the ratchet-teeth will compel the outer part of the handle to move on its hinge, and the abutment a² will force the pawl into the position shown in Fig. 3 with a full hold of one of the ratchet-teeth.

It will now be clear that my invention is the combination of a pawl which obtains a slight hold by gravity with means which automatically compel the pawl to take a full hold, and while the result is obtained in the form shown in Figs. 1 to 2^b, inclusive, by means which compel the pawl to swing toward the axis of the ratchet when the handle is moved to move the ratchet in the form shown in Figs. 3 and 4 by means which compel the pawl to move endwise when the handle is moved to move the ratchet, yet it is obvious that both forms embody my invention, which is the combination of a gravity-pawl (which is sure to take more or less of a hold upon one of the ratchet-teeth, but is not sure to take a full hold) with automatic means to compel that pawl to take a full hold, the new result being that a single gravity-pawl is made to take a full hold, and failure to take a full hold is a mechanical impossibility.

I do not claim hinging the carrier to the handle nor the movable abutment a² and have illustrated that movable abutment as one example of means for automatically compelling the pawl to take a full hold, which may be used as a substitute for the means shown in Figs. 1, 2, 2^a, and 2^b, nor do I claim a pawl

sliding on an inclined plane, as I am aware of Patent No. 558,371 to P. S. Emery, dated April 14, 1896.

What I do claim as my invention is—
5 The combination of a ratchet; a pawl with an inclined lower end; a pawl-chamber with an inclined bottom; and automatic means

which compel the engaging end of the pawl to move toward the axis of the ratchet when the pawl and ratchet are moved as one.
